UNITED STATES PATENT OFFICE.

ZEBULUN COLVIN KETCHUM, OF OTTAWA, CANADA.

PAPER-FILE.

SPECIFICATION forming part of Letters Patent No. 710,586, dated October 7, 1902.

Application filed December 27, 1901. Serial No. 87,422. (No model.)

To all whom it may concern:

Be it known that I, ZEBULUN COLVIN KETCHUM, merchant, a subject of the King of Great Britain, residing at Ottawa, in the 5 county of Carleton, in the Province of Ontario, Canada, have invented a new and useful Paper-File, of which the following is a specification.

My invention relates to improvements in 10 paper-files; and the object of my invention is to devise a paper-file for filing away letters, receipts, statements, or other papers which shall be cheap in construction and may be adjusted in height to firmly hold any number 15 of papers which may be held thereon; and it consists, essentially, of a base having upwardly-extending posts or pins secured thereto, a movable strip to slide up and down on said posts, an eccentric-clamp for securing 20 said movable strip at any desired height on said posts, and suitable upper and lower covers flexibly attached to said base and said movable strip, the various parts being constructed and arranged in detail, as hereinafter 25 more particularly described.

Figure 1 is a perspective view of my file, showing the base and the movable strip covered with any suitable material, such as leather, and with the top and bottom covers 30 attached thereto, and also showing the butterfly-key. Fig. 2 is a plan view of the clamping device, showing the position of its parts when gripping the posts. Fig. 3 is a plan view of the device when loosened. Fig. 4 is 35 a section through Fig. 2 on the line xx . Fig. 5 is a sectional view through Fig. 3 on the line yy . Fig. 6 is a portion of an alternative form of post. Fig. 7 is a view of a completed post of the alternative form. Fig. 8 is a view 40 of the disk and eccentric.

In the drawings like letters of reference indicate corresponding parts in each figure.

A is the base.

B B' are posts or pins which are fastened 45 by riveting or other suitable means to the base A. These posts are preferably circular in cross-section and may be made in one piece, or, if preferable, may be made in sections, as shown in Figs. 6 and 8, to permit of 50 their being lengthened when a large number of papers are held on the file. In this case

the sections are made to screw into each other and the top section b is rounded off and the bottom section b' is riveted into the base.

C is the adjustable strip. Holes c c' are 55 bored in the strip C to receive the posts or pins B B'. The method of clamping this strip in any desired height on the posts B and B' is as follows: A rod D is provided, having an elongated hole or slot d, through which the 60 pin B' passes, and having at its opposite end an enlarged portion d', in which is a circular hole d². E is a circular disk having a central hole e to fit loosely over the pin B. An eccentric e' is formed on the under side of this 65 disk, and this eccentric is designed to fit into the hole d² when the disk is in position on the post B. Holes e² e² are formed in the upper side of the disk E, and a butterfly-key F, having a central hole f to fit over the post B, is 70 provided with downwardly-extending projections f' f', designed to engage the holes e² e². Intermediate of the length of the rod D a hole d³ is formed. A pivot d⁴, having an enlarged head d⁵, is provided, and this pivot passes 75 through the hole d³ and secures the rod D loosely to the adjustable strip C, allowing said rod a small amount of play all around in a horizontal sense. It will now be seen that by turning the disk E into the position shown in 80 Figs. 2 and 4 the eccentric e' will force the rod D to press hard against the post B'. The eccentric itself and the disk E will press firmly against the post B, and thus the rod D will be clamped firmly between the posts B 85 and B', and the adjustable strip c will consequently be held securely from slipping either up or down on the posts B B'.

When it is desired to loosen the strip C, the disk E and the eccentric e' are turned into 90 the position shown in Figs. 3 and 5, preferably by means of the butterfly-key F, and in this position the pressure of the rod D against the post B' is released, and also the pressure of the eccentric e' and the disk E against the 95 posts B B' is released, so that the adjustable strip C is free to move up or down on the posts B B'.

G is a cover of any suitable material, but preferably of wood, which is provided with a 100 depression g on its under side to receive the rod D and is also provided with a hole g' for

the post B and the hole g^2 to receive the disk E. This cover is secured to the movable strip C by means of suitable screws or bolts H.

In using my device in practice it will preferably be covered with suitable material, such as leather, cloth, or the like. Upper and lower covers j, j' are secured to the adjustable strip and the base, respectively, by flexible means to permit of their being readily opened and closed.

It will now be seen that I have invented a file for papers, receipts, letters, and the like which possesses many apparent advantages. First, it is simple and cheap in construction; second, it may be adjusted and firmly held in position to suit any number of papers contained therein, and consequently will not take up any unnecessary space; third, the means of clamping the adjustable strip in position is extremely simple, effective, and easily operated.

I am aware that files have been used in which an adjustable cover slides on posts as in the present device; but the clamping devices used for securing the cover in the desired position have never been satisfactory, as they are difficult to operate and are continually breaking or getting out of order. In my device it will be seen that these difficulties are completely done away with in a cheap, simple, and practical manner.

What I claim as my invention is—

1. In a device of the class described, the combination with the base and the posts secured thereto, of an adjustable strip slidably

held on said posts, a clamping-rod located above said adjustable strip and having a hole or slot at one end to engage one of said posts, and having a circular hole at its opposite end, an eccentric extending into said circular hole 40 and having a hole therethrough, through which the other one of said posts extends as and for the purpose specified.

2. In a device of the class described the combination with the base and the posts secured thereto of an adjustable strip having holes to fit on said posts, a clamping-rod loosely pivoted to said adjustable strip and having a hole or slot at one end and a circular hole in an enlarged portion at its opposite end, and 50 a circular disk having a central hole to fit on one of said posts and having an eccentric to fit in said circular hole in said clamping-rod as and for the purpose specified.

3. In a clamping device for a file of the class described the combination of a clamping-rod loosely pivoted at a point intermediate its length and having a hole or slot at one end and a circular hole at its opposite end and a circular disk having a central hole 60 and an eccentric formed on its under-side and designed to fit in said circular hole in said clamping-rod as and for the purpose specified.

Signed at the city of Ottawa this 23d day of December, 1901.

ZEBULUN COLVIN KETCHUM.
